DESIGN FOR A BILL CLIP OR SIMILAR ARTICLE

Henry L. Lambert and Erwin Schodlbauer, New York, N. Y., assignors to Lambert Bros., Jewelers, Inc., New York, N. Y., a corporation of New York

Application June 14, 1944, Serial No. 113,994

Term of patent 7 years

(Cl. D74—2)

To all whom it may concern:

Be it known that we, Henry L. Lambert and Erwin Schodlbauer, citizens of the United States of America and both residents of the Borough of Manhattan, in the city, county, and State of New York, have invented a new, original, and ornamental Design for a Bill Clip or Similar Article, of which the following is a specification, reference being had to the accompanying drawing, forming part thereof, in which

Fig. 2 is a rear elevational view thereof; and Fig. 3 is a side elevational view thereof.

We claim:

The ornamental design for a bill clip or similar article, as shown.

HENRY L. LAMBERT.
ERWIN SCHODLBAUER.
